UNITED STATES PATENT OFFICE.

PAUL F. HACKETHAL, OF CLEVELAND, OHIO, ASSIGNOR TO RALPH L. SKINNER, OF DETROIT, MICHIGAN.

MOUNTING FOR INTERNAL-COMBUSTION-ENGINE PISTONS.

Application filed February 29, 1928. Serial No. 257,919.

The object of the present invention is to provide simple means for use with the pistons of internal-combustion engines, or the like, whereby to eliminate objectionable, 5 audible, slapping or tapping noises due to the pistons coming into hammering or knocking contact with the walls of their cylinders, certain clearances between such pistons and their cylinders being necessary, especially in 10 those instances where aluminum or alloy pistons are employed in cylinders of different metals, to allow or compensate for the different heat co-efficients of the pistons and the cylinder walls.

15 An additional purpose of the invention is to avoid the relatively-costly, close limits or tolerances now necessarily used between the pistons and their cylinder walls in an attempt to use engines, of the type referred to, 20 which will not have the annoying piston slaps mentioned.

A further aim of the invention is to reduce the friction losses of such reciprocating pistons, especially at their higher speeds of 25 operation.

It has, heretofore, been proposed to overcome such piston noises or slaps by employing a coiled spring for each piston, attached at one end to the lower or skirt portion of 30 the piston, and at its other end to the adjacent part of the connecting-rod, with the object of holding the piston at all times against one side only of the cylinder in which the piston reciprocates.

35 Such a construction, for pistons of the usual diameter and with explosion gas pressures now commonly employed, would require a spring of such force or capacity that its size would preclude its employment in the 40 specified relation in the piston, using spring materials known today and with engines operated at the present-day high speeds.

Furthermore, a spring which would be capable, regardless of its size and the space 45 available, of holding the piston continuously against one side only of the cylinder, would be of such great capacity that the friction produced thereby between the piston and the cylinder, for the complete engine 50 cycle, would be such a materially detrimental factor as would bar its general, practical use.

According to the principles of the present invention, one or more springs are employed in each piston, in such a way as to accomplish the above-stated and other objects without preventing the specified, rocking actions of the pistons into contact with the cylinder-walls, but cushioning such oscillatory movements of the pistons in their cylinders 60 in such a manner as to avoid the occurrence of noisy slaps perceptible to the ear, and also reducing or lowering the piston to cylinder friction at the higher speeds of engine operation.

To enable those acquainted with this art to understand the present invention fully, both from structural and functional standpoints, in the accompanying drawing, forming a part of this specification, and to which 70 reference should be had in connection with the following, detailed description, a present, preferred embodiment of the invention has been illustrated, like reference characters referring to the same parts in the two views. 75

In this drawing,—

Fig. 1 is a longitudinal section through one cylinder and piston, on substantially line 1—1 of Fig. 2, of a multi-cylinder engine; 80 and

Fig. 2 is a cross-section on line 2—2 of Fig. 1, the parts being viewed in the direction indicated by the arrows.

Referring to the views of this drawing, it will be noted that the hollow piston 10, 85 reciprocates in its cylinder 11, and which may be of any convenient or usual form, is equipped with the customary connecting-rod 12 by means of a hollow piston or wrist pin 13 clamped inside a split, upper end of the 90 connecting-rod, by a tightening screw 14, such pin being at, or slightly to one side of, the axis of the piston, as may be preferred.

So far as described, the construction is of 95 the customary form now in common use.

The screw 14 also holds in place a double-ended clip 15, the terminal, downturned ears 16, 16 of which are apertured to receive the hook-shaped ends of a pair of coiled springs 17, 17, the opposite ends of which hook into 100 holes in small plates 18, 18 fastened to the lower portion of the piston-skirt on the side of the connecting-rod opposite the attachment of the spring ends to the clip 15.

As is clearly shown, the ears or lugs 16, 16 and the plates or brackets 18, 18 are spaced apart sufficiently to position or locate the springs on opposite sides of the connecting-rod and out of contact or conflict therewith, the lower end of the connecting-rod being associated with the engine crank-shaft 19 in the usual way.

It is of obvious advantage to place the anchorage of the spring or springs at the connecting-rod end as close as possible to the axis of the piston-pin to reduce the travel of that end of the spring, which is a function of the angularity of the connecting-rod, thereby straining the spring or springs through such a small range as to insure length of operative life thereof.

In the earlier proposed construction, where this attachment point is on the same side of the connecting-rod as the anchoring point to the piston, a certain angle is obtained between the axis of the spring and the vertical piston-wall corresponding to the point of attachment of the spring to the piston, but by securing the spring or springs to the opposite side of the connecting-rod such angle is considerably increased toward the right-angle relation of spring to piston, with the result that each spring acts more advantageously on the piston, permitting a small spring capacity to be employed to perform the required work in view.

By employing such spring forces only as will eliminate the audible, piston noises, without maintaining the piston at all times in contact with one side only of its cylinder, the spring means will function as a cushion or shock-absorber for the rocking piston, when the forces acting on the piston thrust it from one side of its cylinder to the other side, as when the pressure of the exploded gases is suddenly imposed on the top face of the piston to cause its descent, such pressure acting on the piston while its connecting-rod is at an oblique angle thereto.

It will be understood, therefore, that the spring means is so designed and arranged as not to prevent the rocking or oscillatory movements of the piston between the opposite side-walls of the cylinder, or, stated differently, it does not maintain the piston sufficiently rigidly with relation to its connecting-rod to constantly keep the contact of the piston at one side only of its cylinder, but, on the contrary, as the forces acting on the piston tending to thrust or shift it into slapping or hammering contact with either side of the cylinder occur, the spring means will absorb or cushion such movements of the piston sufficiently to preclude the occurrence of annoying, audible slaps, taps, or knocks.

Such desirable result is, in all likelihood, due to the checking or retardation of the

speed with which the piston shifts its position when the spring means is used in the indicated relation.

This avoidance of rapid, powerful, cross-wise, piston-rocking movements in its cylinder, thus excluding the slapping or hammering action referred to, results in reduced piston and cylinder wear.

The capacity or power of the spring means employed depends upon a number of determining influences, such as the gas pressures on the top of the piston, the shape of the combustion-chamber of the cylinder, the location of the spark plug, the diameter of the piston, the weight of the reciprocating parts, the location of the piston-pin in the piston, the ignition timing, etc.

The spring means used to satisfactorily meet the conditions and to perform the functions hereinabove detailed is only a small part of the strength of a spring which would be needed to keep the piston always in contact with one side only of the cylinder, and, accordingly, sufficient space is available inside of the piston to accommodate the spring means performing the peculiar and limited functions to accomplish the results outlined in the manner stated.

The spring means, in addition to avoiding the occurrence of audible, piston slaps, also prevents piston-pin knocks or noises due to the necessary clearance between the piston-pin and its bearing, whether such bearing is in the piston or in the connecting-rod, or in both.

Such highly desirable effect is brought about because the end of the spring or springs anchored to the connecting-rod holds the pin and bearing in sidewise contact adequately to effect a sliding or rolling travel of the pin and bearing relative to one another in the curved path of one side of the bearing, thus removing substantial play of the pin and bearing lengthwise the piston, and hence avoiding such audible, piston-pin noises.

Furthermore, in some instances, there is a tendency for the piston-pin to oscillate more or less sidewise relative to its bearing, at certain speeds or periods of the engine, due to whipping of the connecting-rod, or, in other instances, especially at high engine speeds, owing to the centrifugal action of the reciprocating masses which are under the influences of associated, revolving members, all of which actions, unless prevented, may produce objectionable noises, either by the piston-pin or the piston.

Such distasteful, noisy occurrences are adequately and properly reduced by the employment of the spring means, which, under these circumstances, either maintains the sidewise contact of the piston-pin and bearing or sufficiently cushions the movements

of the pin and bearing relative to one another, or cushions the motions of the piston in the cylinder.

Those acquainted with this art will readily understand that the invention, as defined by the following claims, is susceptible of a variety of satisfactory embodiments, and is not limited to the single, particular embodiment presented herein in detail.

10 I claim:

1. The combination of a cylinder, a piston reciprocatory therein, a crank-shaft, a connecting-rod rockingly mounted on said piston and crank-shaft, and a coiled spring anchored to said piston and to said connecting-rod on the side of the latter opposite such attachment of the spring to the piston and of such capacity as to permit the transverse thrust movements of the piston in the cylinder and to cushion the same sufficiently to substantially eliminate piston slaps audible to the unaided hearing of the average human being.

2. The combination of a cylinder, a piston having a piston-pin reciprocatory in said cylinder, a crank-shaft, a connecting-rod rockingly mounted on said crank-shaft, and rockingly associated with said piston through said piston-pin, one of said elements having a bearing in which said piston-pin turns, and a coiled spring anchored to said piston and to said connecting-rod on the side of the latter opposite such attachment of the spring to the piston and of such capacity as to cushion the relative movements of said piston-pin and its bearing to eliminate noisy play therebetween audible to the unaided hearing of the average human being.

3. The combination of a cylinder, a piston reciprocatory therein, a crank-shaft, a connecting-rod rockingly associated with said piston and crank-shaft, and a spring anchored to said piston and to said connecting-rod on the side of the latter opposite such attachment of the spring to the piston, such spring crossing said connecting-rod and of such capacity as to permit the transverse thrust movements of the piston in the cylinder and to cushion the same sufficiently to substantially eliminate piston slaps audible to the unaided hearing of the average human being.

4. The combination of a cylinder, a piston having a piston-pin reciprocatory in said cylinder, a crank-shaft, a connecting-rod 55 rockingly mounted on said crank-shaft and rockingly associated with said piston through said piston-pin, one of said elements having a bearing in which said piston-pin turns, and a spring anchored to said piston and to said connecting-rod on the side of the latter opposite such attachment of the spring to the piston, said spring crossing said connecting-rod and of such capacity as to cushion the relative movements of such piston-pin and its bearing to eliminate noisy 60 play therebetween audible to the unaided hearing of the average human being.

5. The combination of a cylinder, a piston reciprocatory therein, a crank-shaft, a connecting-rod rockingly associated with said piston and crank-shaft, and a pair of springs anchored to said piston and to said connecting-rod on the side of the latter opposite such attachment of the springs to the piston, the connecting-rod being located between said springs, such springs being of such capacity as to permit the transverse thrust movements of the piston in the cylinder and to cushion the same sufficiently to 70 substantially eliminate piston slaps audible to the unaided hearing of the average human being.

6. The combination of a cylinder, a piston having a piston-pin reciprocatory in said cylinder, a crank-shaft, a connecting-rod 85 rockingly mounted on said crank-shaft and rockingly associated with said piston through said piston-pin, one of said elements having a bearing in which said piston-pin turns, and a pair of springs anchored to said piston and to said connecting-rod on the side of the latter opposite such attachment of the springs to the piston, said connecting-rod being located between said springs, such 90 springs being of such capacity as to cushion the relative movements of said piston-pin and its bearing to eliminate noisy play therebetween.

In witness whereof I have hereunto set my 100 hand.

PAUL F. HACKETHAL.
